DOOR OPERATING APPARATUS

Henry B. Clark, Elizabeth, N. J.

Application October 24, 1944, Serial No. 560,144

9 Claims. (Cl. 268—63)

1

This invention relates to mechanism for opening and closing doors of buildings, particularly doors which include two complementary sections movable toward and from each other in a door-way to close and open said door-way, respectively.

One object of the invention is to provide novel and improved simple, reliable and relatively inexpensive apparatus for simultaneously moving said door sections toward and from each other to close and open the door-way, respectively.

Another object is to provide a combination of such a door-operating apparatus and novel and improved electrical means for actuating said apparatus which shall enable both the opening and the closing movements of the said apparatus to be controlled by only one simple manually operable element such as an electric switch and which may comprise any of several mechanical or electrical methods and mechanisms.

A further object is to provide door-operating mechanism of the character described which shall embody novel and improved features of construction for stopping of operation of the doors by the actuating mechanism and thereby to ensure against injury to the doors or to a person or an object such as a truck or the like in case the doors should accidentally strike such person or object during operation of the doors.

Other objects, advantages and results of the invention will be brought out by the following description in conjunction with the accompanying drawings in which

Figure 1 is an inside elevational view of a wall of a structure having a door provided with operating mechanism constructed in accordance with the invention.

Figure 2 is a horizontal sectional view on the line 2—2 of Figure 1, showing the doors in closed position by solid lines and in open position by dot and dash lines.

Figure 3 is a vertical longitudinal sectional view on the line 3—3 of Figure 2.

Figure 4 is an enlarged transverse vertical sectional view on the line 4—4 of Figure 3.

Figure 5 is a similar view on the line 5—5 of Figure 3.

Figure 6 is an enlarged fragmentary horizontal sectional view on the line 6—6 of Figure 1, showing the selector switch and its relation to the guide track.

Figure 7 is a wiring diagram of the electrical circuit for controlling operation of the motor which drives the door operating mechanism.

Figure 8 is a fragmentary inside elevational view of a modification of the invention, and

Figure 9 is a horizontal sectional view on the line 9—9 of Figure 8.

Specifically describing the embodiment of the invention illustrated in Figures 1 to 7 inclusive, the reference character 10 designates the wall

2

of a garage, boat house, factory building or other structure having a door opening or door-way 11 which is provided with two inwardly swinging doors which are hingedly connected to the frame of the door-way by hinges 12 and each of which is composed of two sections or leaves 13 and 14 hinged together at 15. With this construction, the door sections 13 and 14 of the two doors may be swung into a common vertical plane to close the door opening as shown in Figure 1 and by solid lines in Figure 2 or may be swung inwardly of the door opening to open the latter as shown by dot and dash lines in Figure 2. To insure proper folding and unfolding of the door sections, each endmost section 14 has secured thereto a bracket 16 in which is journaled a guide roller 16 which cooperates with a horizontal channel rail 17 which is stationarily mounted above the upper edges 20 of the door on the wall 10 in any suitable manner. As shown, the guide rail is connected to hangers 18 which are mounted by bolts 19 on the wall 10 above the door opening and support a guide track 20 for the door operating mechanism.

The guide track 20 may be of any suitable construction but is shown as a horizontal split tube of rectangular cross section having a longitudinal slot 21 in its bottom wall. Slidable within the guide track and movable toward and from each other are two guide blocks 22, each of which may be of any suitable construction but is shown as comprising a sheet metal core 23 whose outside dimensions are smaller than the inside dimensions of the track 20 and to which are fastened shoes 24 of suitable material such as lignum vitae. The shoes 24 have a free sliding contact with the inner walls of the track 20 so as to smoothly guide the blocks in the track.

One guide block is connected to the section 13 of each door which is hingedly connected to the door frame and as shown, each door section 13 has an inwardly projecting arm 26 rigidly connected thereto and to which is pivotally connected at 27 one end of a link 28, the other end of which is pivotally connected to a stud 29 which is secured in the corresponding guide block 22.

For simultaneously moving the guide blocks 22 toward and from each other, I utilize two flexible connectors 30, preferably chains, each of which has one end connected to one of the guide blocks 22 as at 31 and its other end connected to the other guide block as at 32. Adjacent each end of the track 20 and preferably within the track is a guide 33 over which passes the intermediate portion of one of the chains 30. Preferably the guides 33 are sprockets and one of them is driven so as to move the chains longitudinally upon rotation of the sprocket. With this construction, it will be seen that upon longitudinal movement of

one of the chains 30 in opposite directions, the guide blocks 22 will be moved toward and from each other respectively so as to close and open the doors. Preferably a grooved idler roller 33' is journaled centrally of the length of the track for guiding the longer reaches of the chains when the guide blocks are adjacent the ends of the guide track 20.

As shown, the driven sprocket 33 is keyed on a shaft 34 journaled in bearings 35 on the track 20 and upon which is also fastened a gear 36 which meshes with a pinion 37 that is fast connected to driving shaft 38. The shaft 38 is journaled in bearings 39 on the track and has thereon a friction clutch which comprises a body section 40 keyed on the shaft 38 and a pulley section 41 rotatable on the shaft and normally held in frictional contact with the body 40 by a compression spring 42. The pulley section 41 is connected by a belt 43 to a smaller pulley 44 on the shaft of an electric motor 45 which for convenience is mounted on the top of the track 20.

In accordance with the invention the motor 45 is reversible and its operation to open and close the doors is controlled by a single simple switch that may be manually operated or might be automatically operated, such as a pneumatic switch in the floor to be operated upon passage thereover of a truck. In the interest of simplicity of explanation, I have shown a simple push button switch 46 which may be mounted in the wall 10. Connected in circuit with the switch 46 is a known type of magnetic controller 47 for the motor 45, a gear limit switch 48 and a selector switch 49. The gear limit switch 48 may be of any suitable construction, for example as shown in U. S. Patent No. 2,221,324 dated November 12, 1940, and includes a driving spindle 50 connected to the shaft 34 on which the driving sprocket 33 for the chains 30 is mounted. The switch also includes two terminal contacts 51 which are connected together and one of which is connected to one terminal of the push button switch 46 by a wire 52 while the other is connected by a wire 53 to one side of the electricity supply line. Each terminal contact 51 has cooperating therewith a contact arm 54 one of which is connected to one terminal of one holding switch 55 while the other is connected to one terminal of the other holding switch 55. The two arms 54 are actuated in known manner by rotation of the spindle 50 so that when one arm engages its corresponding terminal contact 51, the other arm is disengaged from its contact 51.

The selector switch 49 includes two terminal contacts 56 which are connected together and one of which is connected by a wire 57 to the other terminal of the push button switch 46. Cooperating with each of the contact terminals 56 is a contact arm 58 one of which is connected to the other terminal of one of said holding switches 55 while the other is connected to the other terminal of the other holding switch 55. The selector switch 49 is operated by one of the guide blocks 22 and may be of any suitable construction, for example such as described in U. S. Patent No. 2,343,807 dated March 7, 1944. For simplicity in explanation, I have shown a modified construction in Figure 6 of the drawings wherein the switch includes a casing 59 of suitable insulating material which is mounted on a bracket 60 on the guide track 20. The terminal contacts 56 are mounted on the walls of the casing as is also each of the contact arms 58, and said contact arms are shown as inherently resilient so as to

normally engage their respective terminals 56. The contact arms are actuated by a lever 61 pivotally mounted intermediate its ends in the casing and having a roller 62 at one end to engage the contact arms, and a pin and slot connection 63 at its other end with an operating lever 64 which is pivotally mounted at 65 intermediate its ends on the casing and has a roller 66 at its other end extending through an opening 67 in the side wall of the guide track 20 into the path of movement of one of the guide blocks 22. The guide block 22 and the lever 65 are so related that just prior to closing of the doors the blocks 22 will swing the lever 65 in one direction, while when the block moves in the other direction during opening of the doors the lever 65 will be actuated in the opposite direction. When the lever 65 is operated in either direction the lever 61 is operated to release one of the contact arms 58 for engagement with its corresponding terminal contact 56 and to force the other contact arm 58 out of engagement with its contact 56. A tension spring 68 connects the two levers to hold the lever 61 in the last mentioned position.

In operation of the apparatus, assuming the doors to be closed as shown by solid lines in Figures 1 and 2, the manually operable switch 46 will be open as shown in Figure 7. To open the doors the operator will momentarily close the switch 46 and thereupon the magnetic motor controller mechanism 47 will be operated to start the motor and close the right-hand holding switch 55. Then the motor will continue to operate in one direction and drive the chains 30 so as to move the guide blocks 22 away from each other and open the doors. During this operation the selector switch 49 will be operated by the guide block 22 so that upon the next closing of the circuit by the push button switch, the motor will be operated in the other direction. The spindle 50 of the gear limit switch 48 will be driven during the opening movement of the doors and will have been set in known manner so that when the doors approach their full open position the contact arms 54 will be operated so as to stop the motor and at the same time set the switch for reverse operation of the motor upon the next momentary closing of the manually operable switch 46.

When it is desired to close the doors, the manually operable switch 46 will again be closed, whereupon the motor will be started in the direction opposite to that in which it moved during opening of the doors and the left-hand holding switch 55 will be closed to continue the operation of the motor when the switch 46 is released. During the closing movement of the doors the selector switch 49 again will be actuated, and when the doors approach their closed position the gear limit switch contact arms 54 will be operated to stop the motor and set the switch for operation of the motor in the direction to open the doors upon the next closing of the manually operated switch 46.

It will be observed that the guide blocks 22 in conjunction with the two chains 30 in effect form an endless chain but eliminate the complications which would be involved in attempting to utilize a true endless chain. Also the guide blocks in the track ensure a positive smooth-running operating mechanism with a minimum of moving parts. The door may be easily and conveniently operated by the simple manipulation of only one switch, which is operated in the same manner 75 to both open and close the doors, and there is no

danger of the operating mechanism being started into operation in the wrong direction. The friction clutch 41, 40 ensures a stopping of the driving of the chains 30 by the motor should either door encounter an obstruction such as a person or a truck during either opening or closing of the doors.

It will be understood by those skilled in the art that if only one door is to be operated, only one guide block 22 and one chain would be required, the chain having its opposite ends connected to the guide block and one sprocket or guide member being located adjacent each side of the doorway.

Other types of limit switches than those described may be utilized and other electrical or mechanical methods and mechanisms may be used for operating the guide blocks 20. For example, a reversing switch mechanically operated by a lever at each limit of travel of the doors or guide blocks in combination with holding relays for controlling the circuit to the motor, such that at the limit of movement of the doors in each direction one lever would be operated to actuate the reversing switch and one of said relays to stop the motor and to cause operation of the doors in the other direction upon the next momentary closing of the manual operable switch. Another possible mechanism would include a gear limit switch which will control the flow of current in each direction, in combination with relays for controlling the operation of the motor.

A modification of the invention is shown in Figures 8 and 9 where each door includes the two hinged leaves 70 and 71, the latter of which is hingedly connected at 72 to the wall 73 in the same manner in which the doors shown in Figures 1 and 2 are mounted. The outer section or leaf 70 of each door has a guide roller 74 thereon movable in a guide rail 75, which corresponds respectively to the roller 16 and guide rail 17 herein-before described. The rail 75 is mounted on the door frame by suitable brackets 76 and at each end thereof adjacent the point of hinging of the doors to the wall there is an arcuate portion 77 concentric with the axes of the hinges 72 and through which the corresponding roller 74 may move to permit swinging of the door sections completely out of the door opening 78 and into a plane parallel with the plane of the wall as shown by dot and dash lines in Figure 9.

Other modifications and changes in the details of construction of the door operating apparatus, and in the use of the door operating apparatus with other door structures, will occur to those skilled in the art as within the spirit and scope of the invention.

I claim:

1. A door operating apparatus comprising a horizontal track, two guide blocks spaced longitudinally of and movable toward and from each other in said track, two flexible connectors each having one end connected to one of said guide blocks and its other end connected to the other guide block, a guide for each connector around which passes the intermediate portion of said connector such that said guide blocks are moved toward and from each other upon longitudinal movement of either of said connectors in opposite directions respectively, and means for pivotally connecting each guide block to a door.

2. The door operating apparatus set forth in claim 1 with the addition of means for longitudinally moving said flexible connectors.

3. The door operating apparatus set forth in 75

claim 1 with the addition of a motor, mechanism for driving said flexible connectors from said motor, and means whereby said motor may be operated in either of opposite directions as desired.

4. The door operating apparatus set forth in claim 1 with the addition of means for longitudinally moving said flexible connectors, a fixed guide rail mounted above the doors, and means mounted on each door and engaging said rail to guide said door.

5. The door operating apparatus set forth in claim 1 with the addition of a reversible electric motor, mechanism for driving said flexible connectors from said motor, switch mechanism including a switch for closing a circuit to cause rotation of said motor in either direction, and mechanism for automatically stopping said motor when the doors reach a predetermined position during movement in either direction.

6. A door operating apparatus comprising a horizontal split tubular track above the doors and having a longitudinal slot in one side thereof, two guide blocks spaced longitudinally of and slidably mounted in said track for movement toward and from each other, two chains wholly enclosed within said tubular track each having one end connected to one of said guide blocks and its other end connected to the other guide block, a sprocket journaled within said track for each chain and around which passes the intermediate portion of said chain such that said blocks are moved toward and from each other upon movement of either of said chains over its sprocket in opposite directions respectively, a pin secured in each said block and projecting through said slot in said track, links each having one end pivotally connected to one of said pins and its other end to be pivotally connected to a door and means for driving one of said sprockets to move said chains and operate said doors.

7. The door operating apparatus set forth in claim 6 wherein said means for driving said one of said sprockets is a motor and with the addition of means whereby said motor can be operated in either of opposite directions as desired.

8. The door operating apparatus set forth in claim 6 wherein said means for driving said one of said sprockets is a motor and a driving connection including a spring closed friction clutch between said motor and said sprocket, said clutch being capable of yielding to stop driving of said chains upon engagement of either door with an obstacle, and with the addition of means whereby said motor can be operated in either of opposite directions as desired.

9. A door operating apparatus comprising a horizontal split tubular track having a longitudinal slot in one side thereof, two guide blocks spaced longitudinally of and slidably mounted in said track for movement toward and from each other, two flexible connectors wholly enclosed within said track each having one end connected to one of said guide blocks and its other end connected to the other guide block, a guide for each connector around which passes the intermediate portion of said connector such that said guide blocks are moved toward and from each other upon longitudinal movement of either of said connectors in opposite directions respectively, and means including a part extending through said slot in said track for pivotally connecting each guide block to a door.
